UNITED STATES PATENT OFFICE.

HERBERT E. CHURCH, OF ONEONTA, NEW YORK.

COMBINED SHADE-BRACKET AND POLE-SUPPORT.

1,398,418.

Specification of Letters Patent. Patented Nov. 29, 1921.

Application filed January 20, 1921. Serial No. 433,719.

To all whom it may concern:

Be it known that I, HERBERT E. CHURCH, a citizen of the United States, residing at Oneonta, in the county of Otsego and State 5 of New York, have invented certain new and useful Improvements in a Combined Shade-Bracket and Pole-Support, of which the following is a specification.

This invention relates to shade brackets 10 and curtain pole supports.

The object of the invention is to provide a permanently fixed bracket equipped with a detachable adjustable member the position of which may be varied relatively to the bracket to adapt it for use with curtains or shades of different widths.

Another object is to provide a permanently fixed bracket, and a plurality of interchangeable coöperating members for supporting either a shade roller or a curtain pole or both.

Another object is to provide a bracket of this character which may be mounted in different positions on the window frame so that 25 the shade or curtain supported thereby may be hung within or on the frame next to the sash at the will of the user.

With these and other objects in view, the invention consists in certain novel features 30 of construction as hereinafter shown and described and specifically pointed out in the claim.

In the accompanying drawing:

Figure 1 represents a front elevation of 35 a portion of a window one form of this invention shown mounted thereon.

Fig. 2 is a vertical section of the frame with the invention shown in end elevation and in operative position on the frame.

Fig. 3 is a view similar to Fig. 1 showing 40 a different mounting of the bracket.

Fig. 4 is an end elevation thereof shown applied, the window frame being shown in section,

Fig. 5 is a detail end view, with parts 45 broken out of the device constituting this invention.

Fig. 6 is a front elevation showing a 50 slightly different form of the invention detailed.

Fig. 7 is an end elevation thereof.

Fig. 8 is an end elevation of still another form of the invention.

Fig. 9 is an end elevation of still another form of the invention, and,

Fig. 10 is a front elevation of another 55 form of the invention.

In all forms of the invention illustrated the fixed bracket member 1 is the same and comprises a plate constructed of any suitable metal preferably rectangular in form and having one side edge thereof rolled to form a bearing shown at 2, said bearing forming a knuckle or hinge-like connection for the coöperating supporting member presently to be described.

In Figs. 1 and 2 a portion of a window frame F is shown having the usual sash S mounted therein and the device constituting this invention is shown applied to the under 70 face of the cap of the window frame being secured thereto by screws 3 passed through spaced apertures in plate 1 and enters in the frame as F. This plate 1 is provided at one edge with a rolled bearing 2 and opening 75 transversely through one wall thereof and extending through a boss 4 carried by the bearing is a threaded bore designed to receive a set screw 5 extending into the bearing 2 and designed to blindingly engage one 80 arm 11 of a shade roller supporting member 10.

This member 10 is constructed of heavy wire and the end 11 thereof which may be of any desired length is designed to be slidably mounted in the sleeve 2. An arm 12 extends at right angles from one end of the member 11 and is provided at its outer end with a loop-shaped seat 13 to receive one pintle of a shade roller (not shown). At the 85 outer end of the loop 13 the wire is bent downwardly and then obliquely inward to form a supporting brace 14 equipped at its free end with a laterally extending foot 15 which is designed to rest against the window frame at a point below the point of attachment of plate 1 as is shown clearly in Figs. 2 and 4, thereby assists in supporting the shade roller and preventing all possibility 90 of the arm 11 turning in its bearing.

In the form shown in Figs. 7 to 9 the bearing 2 carried by plate 1 is equipped with the right angularly extending boss 4 having a threaded bore communicating with the interior of the bearing and provided with a set screw 5 for securing the arm of member 10 within the bearing 2 of plate 1.

In Figs. 3 and 4 the free end of the member 11^a is threaded as shown at 11^b and has 10 mounted thereon a bur or nut 16 for holding the member 10 adjustably mounted on the bracket 1. In this form of the invention the bracket or plate 1 is shown secured flat against the window frame.

15 In the form shown in Fig. 5 the structure is the same except that the bearing 2^a at one side edge of the plate 1 is made angular or polygonal in cross section and the member 11^a of the roller support 10 is shaped to conform thereto and is held against sliding movement by a set screw 5.

In Figs. 6 and 7 the frame engaging bracket 1 is constructed the same as shown in Figs. 1 and 2. The removable coöperating member however is of a different construction being formed of heavy wire bent to provide an arm 17 slidably mounted in the bearing 2 of the plate 1 and held in adjusted position therein by a set screw 5, 20 while at one end of this arm 17 extends at right angles, an arm 18 having a loop 19 at its outer end to receive and support one of the pintles of a shade roller. After the formation of the loop 19 the wire is folded 25 downwardly against one side member of said loop and then extended obliquely inward to provide a supporting brace 20. From the lower end of this brace 20 the wire is extended upwardly as shown at 21 and 30 bowed intermediate its length as shown at 22 and provided at a point in a plane above the arm 18 with a lateral extension or arm 23 threaded at its free end as shown at 24 and equipped with a bur 25. This arm 23 35 is designed to be passed through a curtain pole P as is shown clearly in Fig. 7 and thus supports the curtain in a plane in advance of the shade which is supported in the loop 19 it of course being understood that two of 40 these bracket members are employed on each window.

The form shown in Fig. 8 is similar to that shown in Fig. 7 except that the laterally extending arm 23^a instead of being 45 threaded at its outer end and equipped with a bur 25 is provided with a seat 26 to receive and support a curtain pole. The wire from which this form of the invention is constructed is here shown angular in cross section and when made of such wire it is of 50 course obvious that the bearing 2^a of the

bracket 1 must conform in cross sectional contour thereto.

In the form shown in Fig. 9 the structure 65 is exactly the same as that shown in Fig. 8 except that the shade and curtain supporting member is made of round instead of angular wire, the plates or brackets 1 in these two figures being shown in different 70 positions.

The form shown in Fig. 10 is the same as that shown in Fig. 9 except that the arm 17^a thereof which is designed to be slidably mounted in the bearing 2 of the plate 1 is 75 threaded throughout its length and has mounted thereon burs or nuts 27 and 28 which are positioned to engage opposite ends of the bearing 2 for securing said arm in adjusted relation relatively to the plate 1.

In Figs. 1 to 4 the device is shown for 80 supporting a shade roller only while Figs. 6 to 10 include curtain pole supporting means.

From the above description it will be obvious that the brackets 1 are designed to be 85 permanently mounted on a window frame being either built therein or secured thereto and the coöperating members 10 and 10^a are interchangeable and adjustable in the bearings 2 of the brackets 1 to adapt them for 90 use with shades and curtains of different widths to support either shade rollers alone or shade rollers and curtain poles both.

The preferred embodiment of the invention is disclosed in the drawings and set forth in the specification, but it will be understood that any modifications within the scope of the claimed invention may be made in the construction without departing from the principle of the invention or sacrificing any of its advantages.

What is claimed is:

A device of the class described comprising an attaching member having a sleeve-like bearing, and a supporting member composed of a single piece of heavy wire with one end adapted to enter said bearing and bent to form a right-angular arm having a shade roller supporting loop at its outer end, said wire being folded down against the outer end of said loop and extended to form an oblique bracing arm having an upstanding member at its lower end for engaging a window frame, the said wire being extended above the said first mentioned arm and bowed outwardly and equipped at its upper end with a forwardly extending right angular arm having a pole receiving seat at its terminal.

In testimony whereof, I affix my signature 120 hereto.

HERBERT E. CHURCH.
